UNITED STATES PATENT OFFICE.

HENRY T. ATKINSON, OF OAKLAND, CALIFORNIA.

WINDOW.

1,239,449.

Specification of Letters Patent. Patented Sept. 11, 1917.

Application filed December 11, 1915. Serial No. 66,310.

To all whom it may concern:

Be it known that I, HENRY T. ATKINSON, a citizen of the United States, residing in the city of Oakland, county of Alameda, State of California, (whose post-office address is 429 Vernon street,) have invented a new and useful Improvement in Windows, of which the following is a specification.

This invention relates more particularly to means for hanging or mounting window sashes in window frames or casements, and to the novel construction and arrangement of the window casings with respect to the sash mounted therein.

In this specification and the annexed drawings, I illustrate the invention in the form that I consider the best, but it is to be understood that I do not limit myself to such form because the said invention may be embodied in other forms, and it is also to be understood that in and by the claims following the description herein, I desire to cover the invention in whatever form it may be embodied.

Referring to the two sheets of drawings: Figure 1 is a front elevation of a window constructed in accordance with this invention, showing the sash in the closed and locked position.

Fig. 2 is a vertical cross section of the same, taken on the line II—II, showing the sash in the advanced position within the vestibule casing.

Fig. 3 is a plan view from the top with the lintel removed showing the sides of the frame in cross section.

Fig. 4 is a detail in end elevation of the supporting hardware, including the sash support and the runway therefor.

Fig. 5 is a longitudinal cross section of the same on the line V—V, the sash support being omitted.

Fig. 6 is a plan view of the lock plate attached to the stool of the window casing.

In detail the construction illustrated in the drawings includes the vestibule window frame, comprising the stool 1 at the bottom, the top plate 2, and the side frames 3 and 4. Within the vestibule frame is the window

frame composed of the bottom rail 5, the lintel 6 and the side stiles 7 and 8, framing the window opening. To this assembly is added the sill 9, the usual exterior trim 10 and 11 and the interior trim 12. The sash may be of any desired pattern, including a frame composed of the bottom rail 13, the top rail 14, and the side stiles 15 and 16,

glazed in the usual manner. This sash frame snugly fits the window openings within the window frame. The top and the two sides of the window opening are slightly tapered, to fit a similar taper on the top and sides of the sash, to insure good weather-tight engagement between the sash and the window frame, that may also be provided with any suitable form of weather strips. The bottom rail of the sash frame is rabbed at 17 to rest upon the rabbeted bottom rail 5 of the window frame, provided with a longitudinal groove 18 having the holes 19 leading therefrom at intervals, to drain off any water that may run down the outside of the sash and collect within the groove 18. The exterior trims 10 and 11 slightly overhang the margin of the window opening to act as a stop as at 20, for the sash frame.

The sash guides 21 and 22 are fixed to the underside of the top plate 2 on opposite sides of the center, parallel with the sides 3 and 4 of the vestibule frame. These guides 21 preferably consist of the plate 23, having the overhanging margin 24 to receive the screws 25 that screw into the top plate 2. These plates 23 are provided with a pair of downwardly extending opposed flanges 26 and 27, forming longitudinal channels 28 with the central openings or slots 29 between the edges of the flanges. The sash is hung on the supports 30 secured to the sash by the screws 31 in alignment with the slots 29 in the said guides. The supports 30 slide freely within the slots 29, the sash being supported by the hemispherical heads 32 slideable within the channels 28 and engaging the lugs 26 and 27. The frame thus supported slides freely from the window opening out into the vestibule frame. In the advanced position, the heads 32 engage the pockets 33 formed in the opposite lugs 26 and 27. The heads 32 descending therein are held by the weight of the sash in that position. The bottom rail 13 of the sash is provided with the bolts 34 and 35 slideable within the brackets 36 and 37 respectively, the bolt being forced down by the expansion of the springs 38 confined within said brackets.

When the sash is in the closed position within the window frame, the bolts 34 and 35 engage the holes 39 in their respective plates 40, fixed to the stool 1 beneath the bolts, the plates 40 are provided with a transverse slot 41, beginning in alignment with the hole 39 and extending inwardly to

ward the center of the stool. When it is desired to move the sash into the advanced position shown in Fig. 2, the bolts 34 and 35 are raised by their convenient handles and 5 permitted to slide along the plates 40, until they drop into the slot 41 under tension of the springs 38. The sash hanging suspended in perpendicular alinement with the plane of the window opening is held at the top by the 10 engagement of the head 32 in the sockets 33 and at the bottom by the bolts 34 and 35. Means may be provided for locking the bolts 34 and 35 by a removable key or other precautionary measure, to prevent burglarious 15 entrance through the window or tampering therewith.

With the sash in the position indicated in Figs. 2 and 3 a margin of space between the 20 interior surface of the vestibule frame and the edges of the sash permits a large volume of air to enter through the vestibule, without creating disagreeable drafts or undesirable air currents. The force of the wind, if any, is broken by the glass X in the sash 25 frame and is directed laterally thereby and caused to enter through the vestibule with the force thereof so diminished as not to be disagreeable. The window being opened at the top as well as at the bottom and sides, 30 perfect circulation of the air within the room is assured, without the disturbance of the draperies, if any, ornamenting the window-frame. In addition to preventing drafts and disagreeable air currents, soot 35 and dirt are excluded from entrance through the window to a very great extent, making it possible to ventilate through the window in the face of a strong wind, or even during a rain storm, without any disagreeable 40 consequences, unless the rain was beating directly against the glass. These are only a few of the many advantages of this invention.

If it is desired to open the window entirely, the bolt 34 is raised out of engagement with the slot 41, and the sash tilted laterally until it unseats the head 32 from the socket 33 on that side of the window sash, bringing the head into coincidence or registry with the opening 42, permitting the entire disengagement of the support 30 from the guide, the length of the slot 41 on the opposite side, permitting the bolt 35 to swing inward toward the center of the stool without disengaging from the plate 40, and permitting the sash to pivot on the support 30 and the bolt 35, so that the sash may be swung open slightly or entirely opened, as indicated in dotted lines in Fig. 1. In this latter position the reverse side of the glass X is presented within the room, a very convenient reversal of the sash for the purposes of washing, eliminating the necessity for hanging out of the window or going outside of 60 the building to wash the outside of the glass. 65

The same operation with respect to the supports and the bolts on the opposite sides of the sash, permit the sash to swing in the opposite direction in an obvious manner. When the sash is in the closed position, as 70 illustrated in Fig. 1, the bolts 34 and 35 engage their respective holes 39 in the plates 40 and lock the sash at the bottom. The pivoted catches 43 and 44 pivoted on opposite sides of the sash, engage the slots 45 formed 75 in the plates 46 fixed to the side stiles 7 and 8 of the window frame, to securely lock the sash within the window opening. The sash may be readily removed from the window 80 frame by releasing all of the various bolts and catches and lifting the heads 32 out of engagement with the guides secured to the top plate 2 which will entirely free the sash from engagement with the frame.

While I have illustrated this invention in 85 connection with the construction of wood, that being the simplest form for illustration, it is to be understood that the invention with ordinary mechanical designing may be formed from pressed metal, in which event 90 much of the interdependent hardware illustrated would be formed integral with the structure of the frame and the sash.

I claim:

1. An improvement in windows comprising 95 a window frame, a sash movable inwardly and outwardly with respect to the frame, means slidably connecting the upper edge of said sash with the contiguous portion of said frame, and means for retaining the lower edge of the sash in closed position when the upper edge has been moved to outward position, said retaining means being releasable to permit the said lower edge to swing outwardly, whereby the sash may assume a vertical open position. 100

2. An improvement in windows comprising 110 a window frame, a sash movable inwardly and outwardly with respect to the frame, means slidably connecting the upper edge of said sash with the contiguous portion of said frame, means for retaining the lower edge of the sash in closed position when the upper edge has been moved to outward position, said retaining means being releasable to permit said lower edge to swing outwardly, whereby the sash may assume a vertical open position, said 115 slidable connecting means being shaped to permit horizontal swinging of the sash when in its outermost position. 120

3. An improvement in windows comprising 125 a window frame provided with spaced apart supports, a sash movable inwardly and outwardly with respect to the frame, means for slidably connecting the upper edge of said sash with said supports, and means for retaining the lower edge of the sash in closed position, said retaining means being releasable to permit said lower edge to swing out- 130

wardly, whereby the sash may assume a vertical open position.

4. An improvement in windows comprising a window frame provided with spaced apart supports, a sash movable inwardly and outwardly with respect to the frame, means for slidably connecting the upper edge of said sash with said supports, and means for retaining the lower edge of the sash in closed position when the upper edge has been moved to outward position, said retaining means being releasable to permit said lower edge to swing outwardly, whereby the sash may assume a vertical open position, said supports and 10 slidable connecting means having complementary portions shaped to permit horizontal swinging of the sash when in its outermost position.

5. An improvement in windows comprising a window frame, a sash movable inwardly and outwardly with respect to the frame, means slidably connecting the upper edge of said sash with the contiguous portion of said frame, and releasable locking devices attached to the lower portion of the sash, said frame being provided with spaced apart recesses to be engaged by said locking devices when the sash is in its innermost and outermost positions, respectively.

30 6. An improvement in windows comprising a window frame, a sash movable inwardly and outwardly with respect to the frame, means slidably connecting the upper edge of said sash with the contiguous portion of said frame, releasable locking devices attached to the lower portion of the sash, and plates attached to said frame and having spaced apart openings positioned to be engaged by said locking devices when the 35 sash is in its innermost and outermost positions respectively.

7. An improvement in windows comprising a window frame, a sash movable inwardly and outwardly with respect to the frame, means slidably connecting the upper edge of said sash with a contiguous portion of said frame, means for rigidly retaining said sash in either its innermost or outermost position, and means coöperating with 45 said retaining means whereby the sash may swing on an axis adjacent either side when the other side is freed while the sash is in open position.

8. An improvement in windows comprising a window frame, spaced apart supports attached to said frame and having sockets at their outer ends, rods attached to the upper edge of said sash and slidably connecting said sockets, and means for retaining the lower edge of the sash in closed position when said rods have been moved into engagement with said sockets, said retaining means being releasable to permit said

lower edge to swing outwardly, whereby the sash may assume a vertical open position. 65

9. An improvement in windows comprising a window frame, spaced apart supports attached to said frame and having sockets at their outer ends, rods attached to the upper edge of said sash and slidably engaging 70 said supports, means for retaining the lower edge of the sash in closed position when said rods have been moved into engagement with said sockets, said retaining means being releasable to permit said lower edge to swing 75 outwardly, whereby the sash may assume a vertical open position, and means coöperating with said retaining means whereby the sash may swing on an axis adjacent either side when the other side is freed while the 80 sash is in open position.

10. An improvement in windows comprising a window frame, spaced apart supports attached to said frame and having sockets at their outer ends, rods attached to the upper 85 edge of said sash and slidably engaging said supports, slidable bolts attached to the lower portion of the sash, said frame being provided with recesses to be engaged by said bolts when the sash is in its outermost position, 90 said bolts being positioned opposite said rods to permit the sash to swing on an axis adjacent either side when the bolt on the other side is disengaged.

11. An improvement in windows comprising a window frame, spaced apart supports attached to said frame and having sockets at their outer ends, rods attached to the upper edge of said sash and slidably engaging 95 said supports, slidable bolts attached to the lower portion of the sash, and plates attached to the contiguous portions of the frame, said plates being each provided with a recess to be engaged by its bolt when the sash is in its innermost position, and a slot 100 to be engaged by its contiguous bolt when the sash is in open position, said bolts being in alinement with said rods to permit the sash to swing on an axis adjacent either side when the bolt on the other side is freed while 105 the sash is in open position.

12. A window frame having a laterally spaced vestibule frame; a sash fitting the opening in said frame; top supports for permitting movement of said sash in said window vestibule parallel with the plane of said window frame; and bottom bolts for pivoting said sash within said vestibule frame by disengaging one of said top supports and one of said bottom bolts.

In testimony whereof, I have hereunto set my hand at San Francisco, California, this 15th day of November, 1915.

HENRY T. ATKINSON.

In presence of—

BALDWIN VALE.
